United States Patent Office.

IMPROVEMENT IN DETACHABLE FLANGES FOR PRIVY BOWLS.

ROBERT DIVEN, OF BROOKLYN, NEW YORK.

Letters Patent No. 60,153, dated December 4, 1866.

SPECIFICATION.

TO ALL WHOM IT MAY CONCERN:

Be it known that I, ROBERT DIVEN, of the city of Brooklyn, in the county of Kings, and State of New York, have invented a new and useful Improvement in Water-Closet Hoppers; and I do hereby declare that the following is a full, clear, and exact description of the same, reference being had to the accompanying drawings, making a part of this specification, in which—

Figure 1 is a vertical transverse section.

Figure 2 is a side elevation, showing a part of the invention.

Figure 3 is a plan view of another part thereof.

Similar letters of reference indicate corresponding parts in all the figures.

This invention consists in a novel combination with a water-closet hopper of a detached flange for securing the hopper to the floor, whereby the said hopper can be easily and conveniently removed for repairs or other purposes, and whereby the hoppers will occupy much less space when packed in quantities for transportation than those hitherto constructed with permanently attached flanges, inasmuch as the hoppers and flanges may be separately packed and transported.

To enable others to understand the nature and construction of my invention, I will proceed to describe it, with reference to the drawings.

A is a water-closet hopper, the upper portion of which is made flaring or bowl shaped, in the usual or any suitable manner, and the lower part or neck of which is tubular in form, as shown more clearly at *a* in fig. 1. Formed around the exterior of the hopper, at the upper end of this tubular neck, is an annular shoulder *b*, which rests upon the detached flange *B* when the hopper is fixed in place upon the floor, as will be presently more fully explained. The exterior of the neck, *a*, is cylindrical in form, except that it has formed upon it three or more lugs or ears *C*, the upper ends of which form shoulders, *c*, opposite and below the shoulder *b*. The distance between the said lugs is equal to or slightly exceeds the width thereof, in order to allow the hopper *A* to be placed upon the flange *B*, fixed to the floor *D*, as will presently appear. The detached flange *B*, a plan of which is shown separately in fig. 3, is secured in a horizontal position to the floor *D*, and over a suitable hole, *m*, therein, as represented in fig. 1, by nails, screws, or any other suitable means, and has a hole, *d*, in its centre, which corresponds in shape with the exterior of the neck *a*, with its lugs *C*, in such manner that the said neck being thrust downward and through the said hole *d* in the flange, the lugs *C* will pass through the recesses *e* and the inwardly projecting spurs *f*, will pass between the lugs *C* on the said neck *a*. The shoulder *b* of the hopper *A* being thus brought down against the flange *B*, the hopper is turned around until the lugs *C* are brought underneath the inwardly projecting spurs *f* of the flange, so that the said spurs *f* are situated between the shoulders *c* of the lugs *C* and the shoulder *b* at the upper end of the neck *a*, and thus hold the hopper *A* securely in position, at the same time that it may be easily removed when desired to be cleaned, or for other purposes, by simply turning the hopper *A* around until the lugs *C* are brought opposite and underneath the recesses *e* in the flange, and then pulling the hopper upwards, the lugs passing through the said recesses. By these means the hopper may be conveniently and quickly secured in place upon the floor, and readily removed therefrom when required. Furthermore, the flanges being removed from the hoppers, the said hoppers may be packed in "nests" for transportation, thus greatly reducing the space ordinarily required for packing the hoppers, the flanges, in this case, being packed separately. It should be mentioned that the upper surface or shoulders *c* of the lugs *C* may be made somewhat inclined or spiral, in such manner that when the spurs *f* are placed between the shoulders *c* and the annular shoulder *b*, as just set forth, they will be forced snugly up against the said shoulder *b*, and thus have a firm bearing upon the same. The flange *b*, instead of being made entirely separate, may be separate only from the body of the hopper, represented above it in the drawing, and be cast with the neck; and in such case the spurs *f* will protrude inwardly beyond the interior of the neck.

What I claim as new, and desire to secure by Letters Patent, is—

The water-closet hopper, constructed with a detached flange *B*, substantially as herein set forth, for the purpose specified, as a new article of manufacture.

ROBERT DIVEN.
